UNITED STATES PATENT OFFICE.

EDWIN S. BROTHERS, OF BROOKLYN, NEW YORK.

DENTAL APPARATUS.

Application filed June 9, 1925. Serial No. 35,855.

This invention relates to dental apparatus and the object of the invention, generally speaking, is to provide an efficient apparatus for the care of the teeth and massaging the gums.

To properly care for the teeth, it is essential that they be kept clean and that proper circulation be maintained in the gums. The invention provides novel tools for accomplishing this result in a thorough and efficient manner, and further provides novel means for attaching said tools to a suitable source of power intended for their operation.

A careful study of the teeth has convinced me that, for their proper treatment, the cleaning and massaging of the teeth at the back of the mouth require greater pressure than at the front of the mouth. To accomplish this result with power driven tools, I have found that in order to obtain the best results, such tools must be formed in a particular and novel manner. These proper pressures can be obtained by forming the tool with a longitudinal taper. The massaging tool is preferably in the form of a soft rubber, longitudinally fluted sleeve fitted over a soft sponge rubber tapered core which is, in turn, fixed to a metal spindle. The spindle is formed to cooperate with a clutch through which is adapted to be driven from a suitable source of power.

A guard is preferably associated with the tool and tooth paste, powder or cream is adapted to be deposited within the guard to be picked up by the tool during operation of the latter.

Features of the invention, other than those adverted to, will be apparent from the herein-40 after detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a central longitudinal section, partly in elevation, of a device embodying the present invention.

Figure 2 is a section on the line 2—2 of Figure 1.

Figure 3 is a central section perspective 55 of the clutch or chuck member, with a frag-

ment of the tool spindle in elevation perspective.

Figure 4 is a like view of the massaging tool.

Referring to the drawings, Figure 4 illustrates a tool embodying the invention and more particularly a massaging roll, designated 2. It will be noted from this figure that the roll tapers to its free end and is of less diameter at its outer end than at its inner end. The purpose of this is that when the tool is manipulated in the mouth, greater pressure is desired on the teeth or gums at the back of the mouth with a lesser pressure at the forward portion of the mouth. These desired pressures can be obtained in a roll by forming the roll as shown in Figure 4. The roll 2 is illustrated as embodying very soft rubber sleeve 6, preferably circumferentially serrated or fluted and fitted over a core 7 of soft sponge rubber 7, which is, in turn, secured to the stem 8 of the tool. The soft core 7 will cooperate to form a pliable and yieldable backing for the soft rubber sleeve 6, so that the latter will not be too harsh on the gums, but will exert thereon a mild massaging effect. The tool is relatively long with respect to its diameter in order to give an effective area of operation and to so distribute their pressure upon the gums and teeth that detrimental abrasion will not result from their use.

In Figure 1, I have shown a hand piece embodying a tubular handle 9, through which extends the envelope 10 of a flexible shaft 11. A chuck or clutch member 12 is secured to the end of the shaft and is driven therefrom. This member is in the form of a short cylindrical metallic block, the rear end of which is solid and in the forward end of which is formed a hole 13 (see Fig. 3) of circular configuration. At the base of the hole 13, a transverse cut 14 is formed in the block 12 and this cut extends substantially one half way through the block, so as to provide a flat sided step 15 at the extreme end of the hole 13. In practice, the hole 13 may, if desired, have a slight taper, so that if the spindles 4 or 8 is slightly tapered and provided with a stepped end 16, as shown in Figure 3, it may be forced into the hole. The stepped end 16 will then interfit with the step 15 at the same time as the spindle becomes tightly seated in the hole and by this construction, 105 110

the spindle is locked for rotation with the chuck.

Associated with the hand piece is a guard 17 which in practice may be made of metal, celluloid or other suitable material. In Figures 1 and 2, the guard is shown as having a metal base 18, to which a non-metallic hood 19 is permanently secured. The base 18 of the guard is in the form of a substantially cylindrical split sleeve 20 adapted to be received into a correspondingly shaped pocket 21 in the end of the hand piece 9. If desired, the sleeve may have a bayonet joint and the hand piece a pin or the parts 15 may be otherwise locked together to preclude relative rotation or inadvertent disengagement of the guard from the hand piece. Beyond the sleeve part 20, the guard is formed with the substantially semicylindrical hood 19 which underlies substantially one half of the tool and the outer end of this hood is closed by an end wall 22 in the interior of which is formed a depression 23 coaxially with the tool so that the outer end of the tool spindle may find a bearing 25 in this depression, whereby the tool is not only steadied during its operation, but is precluded from inadvertent disengagement from the chuck.

In Figure 1, the tool is shown as cylindrical, but it may be tapered like a roll if desired.

As shown in Figures 1 and 2, the hood is preferably provided with an opening or slot 35 24 in its bottom and through this slot tooth paste or cream may be introduced into the hood to be picked up by the tool. Paste may be thus applied in a convenient manner and is not so apt to be thrown off by centrifugal force, as it would be if applied loosely to the exposed face of the tool.

When attaching a tool to, or removing it from the chuck the tool guard is prefer-

ably removed so that the tool may be readily moved longitudinally, but when in assembled relation, the guard is always in place to stabilize the tool and preclude contact of the back of the tool with the surfaces of the mouth.

The device of this invention is simple in construction and thoroughly efficient in its operation. The drawings show the invention in its preferred practical form, but the invention is to be understood as fully commensurate with the appended claims. 55

Having thus fully described the invention, what I claim as new and desire to secure by Letters Patent is:

1. A dental tool comprising a suitable spindle, a yielding core surrounding the 60 spindle and a soft rubber sleeve embracing the core.

2. A dental tool comprising a suitable spindle, a frusto conical yielding core on said spindle and a frusto conical yielding 65 soft rubber sleeve embracing the core, said sleeve being of appreciably greater length than its largest diameter.

3. A dental tool comprising a suitable spindle, a sponge rubber core carried by the 70 spindle, and a soft rubber sleeve embracing the core, said sleeve having a longitudinally fluted exterior.

4. A dental tool comprising a suitable spindle, a yielding core surrounding the 75 spindle, and a soft rubber sleeve embracing the core and having a longitudinally fluted exterior.

5. A dental tool comprising a suitable spindle, a tapering yielding core on the 80 spindle and a tapering soft rubber sleeve embracing the core and having a longitudinally fluted exterior.

In testimony whereof I have signed the foregoing specification.

EDWIN S. BROTHERS.
